United States Patent Office

Des. 179,328

Patented Nov. 27, 1956

179,328

CHOCK OR SIMILAR ARTICLE

Donald E. Stewart, Grand Rapids, Mich., assignor to
Jervis Corporation, Grandville, Mich., a corporation of
Michigan

Application March 5, 1956, Serial No. 40,455

Term of patent 14 years

(Cl. D54—11)

Fig. 1.

Fig. 2.

Fig. 3.

Fig. 4.

Fig. 5.

Fig. 1 is a perspective view of a chock or similar article showing my new design;

Fig. 2 is a top plan view;

Fig. 3 is a side elevational view;

Fig. 4 is an elevational view looking at the right of Fig. 3; and

Fig. 5 is an elevational view looking at the left of Fig. 3.

I claim:

The ornamental design for a chock or similar article, substantially as shown.
